UNITED STATES PATENT OFFICE.

GAYLORD LOGAN, OF ALBANY, NEW YORK.

FILM-HOLDER.

No. 902,153.

Specification of Letters Patent.

Patented Oct. 27, 1908.

Application filed March 5, 1906. Serial No. 304,221.

To all whom it may concern:

Be it known that I, GAYLORD LOGAN, a citizen of the United States, and resident of Albany, in the county of Albany and State of New York, have invented certain new and useful Improvements in Film-Holders, of which the following is a specification.

My invention has for its object to provide means adapted to hold and protect photographic films, so as to permit them to be readily inspected without being handled, and also to provide means to prevent oppositely disposed films from rubbing against each other. Such objects I accomplish by 15 the means illustrated in the accompanying drawings, in which

Figure 1 is a perspective view of a holder embodying my invention, and Fig. 2 is a perspective view of a separating leaf 20 detached from the holder.

As illustrated in the drawings, B represents an elongated band provided with retaining strips, b, preferably formed by folding the lateral margins of the band, B, over 25 onto the body of said band. The band, B, is divided into separate sections by means of creased transverse lines which permit the sections of the holder to be folded together.

The separate sections of the body of the 30 band, B, are preferably cut away, forming openings b' in the sections. I prefer in most instances to provide the band, B, with an auxiliary back of transparent material so as to furnish a support for the body of the films, 35 such auxiliary backing may be made in one continuous strip, D, held in place by the retaining strips, b, or otherwise secured to the face of the band, or individual leaves or transparent material may be secured to the 40 individual sections of the holder if desired. In order to protect the faces of oppositely disposed films I prefer to insert between the sections of the holder an auxiliary separating sheet, C, of paraffin paper or other 45 material having similar capabilities, which prevents the faces of two oppositely disposed films from rubbing together. Said auxiliary separating sheets may be constructed with a binding strip, e, which may be fastened to 50 the face of the band forming the holder or otherwise secured thereto, or left free from the holder.

What I claim as new, and desire to secure by Letters Patent, is:

1. A film holder comprising an elongated 55 band divided into sections by means of creased transverse lines, and having a backing of transparent material, and retaining strips extending along the outer portions of said backing.

2. A film holder comprising an elongated band having retaining strips folded over onto the body of the band, and creased transverse lines dividing said body and retaining strips into separate sections and a separating leaf 65 arranged between two oppositely disposed sections.

3. A film holder having an elongated band divided into sections by means of creased transverse lines and provided with retaining 70 strips folded over on to the face of the band and with openings formed in said sections, and a back formed of transparent material, substantially as shown and described.

4. A film holder having an elongated band 75 divided into sections by means of creased transverse lines, and provided with retaining strips folded over on to the face of said band, with a transparent back, and a separating leaf arranged between two opposite sections, 80 substantially as shown and described.

5. A film holder having the combination of an elongated band provided with retaining strips folded over on to the face of said band, and divided into sections by means of creased 85 transverse lines, a back of transparent material, and a separating leaf of paraffin paper arranged between two opposite sections, substantially as shown and described.

6. A film holder having an elongated band 90 divided into sections by means of creased transverse lines and provided with retaining strips folded over onto the face of the band and with openings formed in said sections substantially as shown and described.

Signed at Albany, in the county of Albany and State of New York this 21st day of February A. D. 1906.

GAYLORD LOGAN
